CLAIM

The ornamental design for a front lower bumper splitter, as shown and described.

DESCRIPTION

FIG. 1 is a front left perspective view of a front lower bumper splitter according to the present invention.

FIG. 2 is a rear right perspective view of the front lower bumper splitter shown in FIG. 1.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof; and,

FIG. 9 is another front view of the front lower bumper splitter shown in FIGS. 1-8, but mounted on a vehicle and with the rest of the vehicle shown in broken lines. Any elements shown in broken lines form no part of the claimed design, but are instead included to show environmental aspects thereof.
